METHOD FOR DRYING BURLAP BAGS

Lloyd T. Bromfield, New York, N. Y.

Application February 25, 1932, Serial No. 595,010

3 Claims. (Cl. 34—24)

This invention relates to the art of drying fiber or fabric bags, the invention being more particularly related to improvements in the method and process of air-drying burlap bags of the kind 5 commonly employed for containing and shipping sugar.

As is well known, burlap bags are produced from strands of hemp, jute or similar plant fibers. The strands are woven together to form the bagging fabric, the character of the weaving being such as to provide a mesh-like structure with air interstices between the contiguous or touching strands. The bagging fabric produced from these plants possesses the quality of absorbing 10 moisture, not only from moist weather but also from the sugar which itself possesses high moisture abstracting properties. The material of the bags is injured if permitted to remain in a moist state for periods of time. A wet condition is undesirable since it adds to the cost of transportation of such bags, and also aids in the disintegration 15 of the fabric of the bags. Certain methods of drying bags are now in use, but they have the disadvantage of requiring large space and also 20 constitute fire hazards for bag stock; and produce a very objectionable smoke, believed to be a product of distillation of the bag fiber binder.

The present invention has for its purpose and object the provision of an improved method and 25 process for thoroughly drying the bags for filling or for laying them aside in readiness for filling, and it overcomes the objections above referred to.

According to the invention, the drying medium 30 consisting of dry or heated air or other suitable drying gas is introduced into the bag under pressure while the entire outside of the bag is kept free and uncovered in an atmosphere of lower pressure so that the drying medium will pass rapidly through the fibers and interstices of the bag and through all parts of the material of the bag, from the high pressure inside area to the low pressure outside area. By introducing the drying 35 medium under pressure, the bag is inflated, thereby stretching the fibers and enlarging the interstices and hence subjecting all parts of the fibers to the action of the flowing medium so as to permit rapid absorption of the moisture pervading the fibers and thereby to effect rapid and thorough drying of the same. To further hasten 40 the drying, the inflated bag may be bodily moved through a drying chamber from which the air is being constantly withdrawn in order that the moisture-laden air, issuing from the bag, will be promptly removed therefrom.

An apparatus suitable for quickly and thor-

oughly drying the bags in accordance with the principles of the present invention is illustrated and described in my companion application, Serial No. 612,030, filed May 18, 1932.

The principles of the invention and the preferred methods and modes of carrying the same into effect in a practical way will be best understood by referring to the accompanying drawing, more or less diagrammatical in character, and in which:

Figure 1 is an elevation and section, showing the general arrangement for subjecting the bag to the drying air;

Fig. 2 represents an exaggerated fragmentary detail section through the material of the bag, 15 showing the pressure drying air acting on the individual fibers;

Fig. 3 is an elevation and section showing a drying chamber through which a number of bags may be bodily moved for drying at one time, 20 and showing also a circulating system for the drying air; and

Fig. 4 represents a top plan view of the parts shown in Fig. 3.

The principles of my invention and the mode 25 of carrying them into effect in a practical way may be employed in connection with any type of apparatus having a blower or compressor for forcing the dry or heated air or other suitable medium into the bag under pressure, the apparatus shown diagrammatically in the accompanying drawing being presented as an example to demonstrate the mode in which the bag or bags may be subjected to the action of the drying medium for effecting rapid and thorough drying. 30

In carrying my invention into effect, the bag 10, to be dried, may be hung or suspended from an overhead plate 11 having a set of depending fingers 12 with which the bag is engaged at its open mouth so that the rim edge of its mouth will 35 be positioned in contact with the underface of the plate. The fingers 12, of which there may be four in number, may be mounted for adjustment with respect to one another so as to spread and stretch the bag at its mouth for retaining 40 the bag by frictional engagement. I may also provide, depending from the plate 11, a movable auxiliary finger 13 by means of which to further stretch the mouth of the bag and tighten its frictional engagement upon the fingers so as to 45 prevent any accidental dropping movement or release of the bag.

14 denotes a blower or compressor for forcing the drying medium such as dry or heated air or other suitable drying gas through the conveying 50

pipe 15 and then into the interior of the bag. The dry air, being introduced into the bag under pressure, creates high pressure within the bag, inflating it and stretching the strands 16 therefore of and also enlarging the interstices 17 between the strands.

The pressure of the dry air within the bag exceeds the atmospheric pressure surrounding the bag; and throughout the material of the bag the 10 drying air will strike and penetrate the strands and pass all around the same, and through the interstices 17 in escaping to the low pressure area surrounding the bag. Little streams of the drying medium are forced through and around the 15 fibers of the fabric. The moisture in the fibers and in any sugar particles adhering to the fibers is absorbed by the dry air and carried off thereby, thus enabling quick and thorough drying, and this is accomplished without any distilling action 20 upon the natural oils of the fibers. The dry air may be, and preferably is, heated prior to its introduction into the bag, but it is not heated to an extent sufficient to have any distilling action 25 upon the fiber oils, although it is nevertheless heated sufficiently to effect a rapid abstraction 30 of the moisture in the fibers and in the sugar particles adhering thereto, to the end that the adhesion between the fibers and sugar particles will be weakened for hastening and completing the detachment and removal of such particles by the maintained force of the air flow 35 itself. Good drying effects, without causing any distillation of the oils, can be had by using air which is heated about 365° F., impinged against a wet bag, whereas for a drier bag a temperature 40 of about 185° F. is suitable. Since there is no distillation of the oil, there is no odor in the utilization of my method.

The foregoing description relates particularly 45 to washed sugar bags. In case it is desired to dry wet or moist unwashed sugar bags, then the bags are turned inside out, and the air is of a lesser temperature, say about room temperature, and any sugar particles adhering to the bag can be removed.

50 The drying process will be hastened by enclosing the bag in a drying chamber 18 disposed immediately below the overhead plate 11 so that the bag will hang freely in the chamber. By the use of a suction fan or exhauster 19, arranged in the outlet conduit 20 of the chamber, a forced withdrawal of the air from the chamber is accomplished so that a low pressure area is produced around the outside of the inflated bag, simultaneously with the introduction of air under 55 pressure into the interior of the bag. By decreasing the atmospheric pressure outside the bag through suction, the force of the flow of the drying air is accelerated and the moisture is carried away more rapidly, with the result that thorough drying of the bag is accomplished in a shorter period of time.

In Figs. 3 and 4, I illustrate how a number of bags may, at one time, be subjected to the drying 60 action of heated air blasts, and in connection with this I illustrate a circulating system in which the hot air, after being once used for drying, is circulated back to the bags for reuse in the drying process.

65 In these illustrations, 21 designates an annular drying chamber the top of which is closed by a rotatable ring plate 22 which supports a number of bags within the drying chamber. The ring plate 22 is supported from a hollow rotary disk structure 23 by means of air delivery pipes 24. There 70 is one delivery pipe for each bag; and the delivery

75 pipes are located in such spaced-apart relation that the bags within the drying chamber 21 will be spaced from one another when inflated. The disk structure 23 is supported by a central distributing head 25 which is rotatably associated with a stationary distributing head 26. The interior of the disk structure 23 is divided by radial partitions 27 into compartments or passages 28 of which there is one for each of the delivery pipes 24, while the stationary distributing head is divided into compartments 29 and 29' by the partition walls 30 and 30', so that air received in the compartment 29 will pass directly into the passages 28 which come directly therebelow, and further so that air received in the compartment 29' 15 will pass directly into the passages 28 which come directly below the same. Air is conducted under pressure into the compartment 29 through a pipe 31 from the blower or compressor 32 with which is associated a heating element 33 for heating the 20 air. As the disk structure 23 revolves, the bags move with it through the orbit afforded by the annular drying chamber. Through each passage 28 that comes in open communication with the compartment 29, a blast of the heated air will 25 rush for escape through the associated delivery pipe 24 and thence into the interior of the bag suspended from the annular plate 22 immediately below such pipe. A suction fan 34 withdraws the air from the drying chamber and forces it 30 through a pipe 35 into the compartment 29', whence the withdrawn air is used over again in the drying operation, it being obvious that through each passage 28 that passes in communication with the compartment 29' a rush of air will take 35 place into the delivery tube associated with such compartment. A suction fan 36, located in a position diametrically opposite the suction fan 34, is provided for withdrawing air from the drying chamber 21 and for exhausting the withdrawn 40 air through an exhaust pipe 37.

This arrangement provides for the drying of a 45 number of bags at one time and possesses the advantage that the bags are bodily in motion through the drying chamber while they are subjected to 50 the drying medium under pressure. The bags are moved in their orbit in the direction of the arrow γ so that they will be first subjected to the drying action of the air flowing from the heating element 33 through the compartment 29. The heated air which reaches the bags through the compartment 29, naturally gives up some of its heat in passing through the bags, so that the air which reaches the bags through the compartment 29' is 55 cooler than the air which passes through the compartment 29. In this system of recirculation of the air, the bags are first subjected to the drying action by air under pressure at the highest desired temperature, and then to a drying action by air under pressure at a lower temperature.

In its simplest aspect, my improved method 60 consists in passing dry or heated air under pressure through and around the bagging strands so that from the hemp and jute fibers composing 65 such strands the objectionable moisture will be absorbed and removed and, for all practical purposes, drying effected without distilling or injuriously affecting the natural oils of the fibers.

Other modes of applying the principles of my 70 invention may be employed, instead of the selected ones herein given for clearness of understanding only, and no unnecessary limitations should be understood therefrom, as I desire to avail myself of all adaptations and modifications 75

permitted to me within the spirit and scope of the appended claims.

I claim:—

1. In a continuous method of drying the moist fibrous material of a plurality of bags for containing sugar or the like, the steps which consist in passing separate portions of a quantity of heated air through the fibrous material of individual bags thereby effecting a preliminary drying of the material of the bags and cooling the air by the absorption of heat therefrom by the material of the bags, subsequently passing separate portions of the air which was cooled during the preliminary drying treatment, through the fibrous material of other individual bags previously subjected to the preliminary drying treatment, continuing the application in a similar way of separate portions of heated air and in a similar way of separate portions of the cooled air until substantially all of the original moisture content of the fibrous material of all the bags is removed.
2. In a continuous method of drying the moist fibrous material of a plurality of bags for containing sugar or the like, the steps which consist in collecting a quantity of drying air, dividing the quantity into separate portions which are forcibly passed through the fibrous material of the individual bags, thereby effecting a preliminary drying of the same, collecting a quantity of the used air and dividing the same into separate portions which are forcibly passed through other individual bags previously subjected to the preliminary drying treatment, continuing forcible application of portions of the drying air in a similar way and forcible application of used air in a similar way until substantially all of the original moisture content of the fibrous material of all the bags as removed.

3. In a method of removing enmeshed sugar particles from, and drying, the moist material of a burlap sugar bag, the steps which consist in expanding the mouth-opening edge portion of the bag to an extent effective to suit extensive expansion of the bag body, by applied retaining means supporting the bag body from said edge portion in gravity pending position and entirely free of the retaining means from the edge portion, entirely covering over the expanded mouth-opening to enclose the chamber of the bag, passing drying fluid while the bag is so suspended, into the chamber of the bag under unrestrained force and in an amount sufficient to expand the bag body outwardly in every direction thereby effectively stretching the fibers of the bag and enlarging the pores thereof throughout the area of the bag, simultaneously maintaining the fluid of application at a temperature sufficiently high, while avoiding any distilling action of the fiber oils, to cause removal by abstraction of the moisture contained in the fibers and in the therein enmeshed sugar particles, such removal of moisture being effective to bring about a weakening in the adhesion between the sugar particles and the stretched fibers, and simultaneously maintaining the whole amount of fluid within the bag chamber under a controllable pressural force greater than the weakening adhesion between the sugar particles and the stretched bag fibers, thereby without inherent injury to the bag to detach and remove sugar particles from the fibers thereof while at the same time to remove the moisture content of the fibers and thoroughly dry the bag in its entirety.

LLOYD T. BROMFIELD.
